DESIGN FOR A LAPEL FOB WATCH

Saul Plosky, New York, N. Y.

Application September 20, 1944, Serial No. 115,373

Term of patent 7 years

(Cl. D42—8)

To all whom it may concern:

Be it known that I, Saul Plosky, a citizen of the United States and a resident of the city of New York, Borough of Manhattan, county and State of New York, have invented a new, original, and ornamental Design for a Lapel Fob Watch, of which the following is a specification, reference being had to the accompanying drawing, forming part thereof.

Fig. 1 is a front view of a lapel fob watch, showing my new design.

Fig. 2 is a rear view; and

Fig. 3 is a side view of the same.

I claim:

The ornamental design for a lapel fob watch, substantially as shown.

SAUL PLOSKY.
